UNITED STATES PATENT OFFICE.

ZERAH H. TATE, OF ERLANGER, KENTUCKY.

DESIGN FOR A BUFFER-SPRING.

SPECIFICATION forming part of Design No. 31,372, dated August 8, 1899.

Application filed July 14, 1899. Serial No. 723,857. Term of patent 14 years.

To all whom it may concern:

Be it known that I, ZERAH H. TATE, a citizen of the United States, residing at Erlanger, Kenton county, State of Kentucky, have invented and produced a new and original Design for a Buffer-Spring, of which the following is a full, clear, and exact description.

Reference is to be had to the accompanying drawing, in which the figure is a perspective view illustrating my design.

The design consists in the buffer-spring having two diverging members A and B, merging into each other at the point C, and of which the member A is slightly undulating and the member B is slightly curved, an opening D appearing in the outer end of the

member B and a rectangular plate E appearing on the free end of the member A.

The essential feature of the design consists in the diverging members and the plate appearing at the outer end of one of said members.

Having thus described my invention, what I claim, and desire to secure by Letters Patent, is—

The design for a buffer-spring, substantially as herein shown and described.

ZERAH H. TATE.
